CLAIM

The ornamental design for a display screen or portion thereof with graphical user interface, as shown and described.

DESCRIPTION

The FIGURE is a front view of a display screen or a portion thereof with graphical user interface showing the claimed design. The outermost rounded rectangle depicted by dash-dot broken lines in the FIGURE shows a perimeter of a display screen or portion thereof and forms no part of the claimed design. The dashed broken lines within the perimeter of the display screen or portion thereof in the FIGURE show portions of the graphical user interface that form no part of the claimed design.
